CLAIM

The ornamental design for an electric cosmetics brush handle, as shown and described.

DESCRIPTION

FIG. 1 is a perspective view of an electric cosmetics brush handle showing my new design;

FIG. 2 is a reduced front view thereof;

FIG. 3 is a reduced rear view thereof;

FIG. 4 is a reduced side view thereof;

FIG. 5 is a reduced top view thereof; and,

FIG. 6 is a reduced bottom view thereof.

The structure shown in broken lines in FIGS. 1 and 2 illustrates a portion of the brush handle that forms no part of the claimed design.
